DESK TELEPHONE

George M. Janda, Westchester, Ill., assignor to Automatic Electric Laboratories, Inc., Northlake, Ill., a corporation of Delaware

Filed Nov. 30, 1967, Ser. No. 9,587

Term of patent 14 years

(Cl. D26—14)

FIG. 1 is a front elevational view of a desk telephone showing my new design;

FIG. 2 is an elevational view of the desk telephone showing one side, the other side being a mirror image of the side shown; and

FIG. 3 is an elevational view of the desk telephone as seen from the back.

The dominant features of my design reside in the portions shown in full lines.

I claim:

The ornamental design for a desk telephone, as shown and described.
